INTERCHANGEABLE SPINNING CAP

Thomas A. Darr, Cumberland, Md.

Application May 18, 1934, Serial No. 726,396

1 Claim. (Cl. 118—62)

The invention relates to caps for spinning spindles of spinning machines and more especially to an interchangeable spinning cap.

The primary object of the invention is the provision of a cap of this character, wherein the bushing for the spindle in a spinning machine is readily replaceable and also the bell of such cap, thereby obviating the necessity of the substitution of an entirely new cap when these parts become worn or unfit for use.

Another object of the invention is the provision of a cap of this character which is simple in construction, thoroughly reliable and efficient in its purpose, readily and easily applied to and removed from the spindle on which the silk bobbin travels, strong, durable, and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is an elevation of a cap constructed in accordance with the invention.

Figure 2 is a bottom plan view.

Figure 3 is a sectional view on the line 3—3 of Figure 2 looking in the direction of the arrows.

Figure 4 is a sectional view showing the bell and the bushing removed or detached.

Figure 5 is a side elevation partly in section of the bushing.

Similar reference characters indicate corresponding parts throughout the several views in the drawing.

Referring to the drawing in detail, A designates

generally the stationary spindle on which travels the rotatable bobbin B as conventionally used in a silk spinning machine, while C is the pulley for supporting the bobbin, and upon the stationary spindle A is hung the cap constituting the present invention and hereinafter fully described.

The cap constituting the present invention comprises a circular head 10 having a central hub 11 and a marginal annular rim 12, the latter being provided with internal threads 13. The hub 10 is of hollow formation and is formed at its outer end with an inturned annular shoulder 14, while fitted within this hub is a removable bushing 15, the latter having a central opening 16 for receiving the upper end of the spindle A, the opening being shaped correspondingly to the upper end of said spindle for snug fitting thereon.

Separately connected with the hub 10 is a cylindrical bell 17, the same having an externally threaded end 18 for fitting with the threads 13 in the rim 12 of the head 10.

It will be obvious that the bushing 15 when becoming worn can be replaced by a new bushing and likewise when the bell 17 becomes rough or otherwise imperfect, such bell can be detached and a new bell substituted, or, the worn or disturbed bell 17 can be refinished, as the occasion may require.

What is claimed is:

A cap of the kind described comprising a circular head having a central hollow hub projected from one side thereof and a marginal annular rim extended from its other side, a bushing snugly fitted in and removable from the hollow hub and having an annular recess in its outer end, an overlap annular flange at the outer end of the hub for seating in said recess, and a bell detachably connected with the rim of said head.

THOMAS A. DARR.
